EX

OR D 11,175

No. 11,175

April 29, 1879

UNITED STATES PATENT OFFICE.

NICHOLAS S. VEDDER, OF TROY, NEW YORK, ASSIGNOR TO CHARLES NOBLE
AND FRANCIS P. NICHOLSON, OF PHILADELPHIA, PENNSYLVANIA.

DESIGN FOR COOKING-STOVES.

Specification forming part of Design No. **11,175**, dated April 29, 1879; application filed April 2, 1879.
[Term of patent 7 years.]

To all whom it may concern:

Be it known that I, NICHOLAS S. VEDDER, of Troy, New York, have produced or invented a new and original Design for a Cooking-Stove, of which the following is a specification.

My design for a cook-stove is fully shown in the accompanying drawing, which represents a perspective view of the stove.

The oven-door has an outer border, *a*, and the body of the door is raised above the outer edge, and has a border, *b*, following its contour. This border is composed of line-work, as shown, and has a shield at the top and at each of the lower corners. The most prominent ornament of the door, however, is the central ornament, *d*, which comprises a medallion, representing the helmeted head of a knight, draped flags arranged on each side of the medallion, and a crown surmounting the same.

The side doors of the fire-place have an outer border and a raised central portion, also bordered, and having a central ornament, *e*, consisting of a medallion similar to that on the oven-door, said medallion, however, being arranged on a shield-shaped base.

The front door of the fire-place has a beaded

border, and has three glazed windows, *f*, between which are panels *i*, carrying shields *m*.

The feet of the stove have raised borders and a central medallion, *n*, of a character similar to that on the oven-door.

I claim—

1. The design for the oven-door having the central ornament, *d*, as shown and described.
2. The design for the oven-door having the central ornament, *d*, and border *b*, as shown and described.
3. The design for the end door of the fire-place, having the central ornament, *e*, as shown and described.
4. The design for the front door of the fire-place, having the glazed windows *f*, the panels *i*, and shields *m*, as shown and described.
5. The design for the feet of the stove, having medallions *n*, as shown and described.

In testimony whereof I have signed my name to this specification in the presence of two subscribing witnesses.

NICHOLAS S. VEDDER.

Witnesses:

JAMES E. CURRAN,
AUSTIN F. PARK.
